FIG. 4.

INVENTOR

Charles F. Lavalle

by his attorney, Quincy May

ATTORNEYS

UNITED STATES PATENT OFFICE.

CHARLES F. LAVALLE, OF NEWMARKET, NEW HAMPSHIRE.

LOOM.

Application filed January 31, 1922. Serial No. 533,077.

To all whom it may concern:

Be it known that I, CHARLES F. LAVALLE, a citizen of the United States, residing at Newmarket, in the county of Rockingham 5 and State of New Hampshire, have invented new and useful Improvements in Looms, of which the following is a specification.

This invention relates to a marquisette loom which includes a comb adapted to extend across and engage a series of warp threads, and reciprocated longitudinally to impart lateral movement to the threads engaged therewith, as in well known looms for weaving gauze or leno fabric.

One object of the invention is to provide improved means for supporting a marquisette comb, in such manner as to permit a quick and convenient removal and replacement of the comb, and to set up an operative connection between the comb and the mechanism which reciprocates it, solely by the operation of lowering the comb upon two rests which support it in its predetermined position in the loom.

Another object is to provide improved means for stopping the loom in case of excessive tension on the warp threads, an element of said means being adapted to constantly maintain a suitable tension on the threads, and being responsive to an excessive tension on the threads to stop the loom.

The invention is embodied in the improvements which I will now proceed to describe and claim.

Of the accompanying drawings forming a part of this specification,—

Figure 1 is a fragmentary front elevation, showing parts of a loom, including the parts in which my invention is embodied.

Figure 2 is a fragmentary top plan view of one end portion.

Figure 3 is a fragmentary top plan view of the opposite end portion.

Figure 4 is a section on line 4—4 of Figure 1.

The same reference characters indicate the same parts in all of the figures.

The marquisette comb which extends cross-wise of a loom for weaving gauze or leno fabrics, is usually composed of a tubular rod or pipe 12, supported longitudinally

and a longitudinal row of teeth or dents 13, fixed to and projecting downwardly from the rod. The comb is located above the warp threads 14, carried by the usual harness (not shown), and is adapted to receive said warp threads when the harness has been moved upwardly to its highest position, and the threads 14 form the top of the shed. In this position the warp threads 14 are above the 60 warp threads 15, forming the bottom of the shed, these warp threads being carried by upright needles 16, of the needle harness 17. The comb is longitudinally reciprocated with a slow motion, to impart lateral movements to the warp threads engaged with it, as usual, in a loom of this type.

My invention, so far as the comb is concerned, is embodied in the improved means next described for supporting and reciprocating the comb, said means being adapted to permit a quick and convenient removal of the comb in the event of a smash or breakdown of the yarn, and a correspondingly quick and convenient restoration of the comb 75 to its operative condition.

The comb rod 12 is provided at its opposite ends with downwardly facing end portions or extensions 18 and 19, each preferably formed as a separate piece, and having 80 a shank which is inserted in the bore of the rod, and secured therein as by a cotter-pin 20. Each extension has an aperture 21. The downwardly facing surface of the comb extension 18, bears loosely on a rest 22, formed 85 as a bracket attached to the upper arm 23 of a two-armed lever which is pivotally connected by a fulcrum bolt 24, with an ear 25, fixed to one of the loom sides 26. The lower arm 27 of said lever is angular, as shown 90 by Figure 1, and is connected by a link 28 with a notched arm 29, which is slowly oscillated in a vertical plane in the directions indicated by the arrow in Figure 4, by suitable connections (not shown) with the driving-shaft of the loom.

The rest 22 is provided with an upstanding pin 30, which loosely enters the orifice in the comb extension 18, and couples said extension to the rest. The oscillations of the arm 29 are imparted to the two-armed lever through the link 28, and the upper arm 23

of said lever is thus oscillated in the directions required to longitudinally reciprocate the comb, the movements of the arm 23 being imparted to the comb through the pin 30 and extension 18, said extension being movably supported and confined against independent horizontal movement by the pin 30.

The extension 19 at the opposite end of 10 the comb bears loosely on a rest 23, formed as a sleeve which is adapted to rock on a horizontal axis formed by a stud 33, supported by a fixed ear or bearing 34 on the arch stand 35^a above the opposite loom side 15 35. The rest 32 has an upstanding pin 36, which loosely enters the aperture in the comb extension 19, and couples said ear to the sleeve. The extension 19 is therefore movably supported and confined against 20 horizontal displacement by the pin 36. The described construction permits the comb and its extensions to be lifted clear of the pins 30 and 36, and removed from the rests and from the loom, and to be deposited on the 25 rests by moving its ears downwardly on the pins. There is no positive connection between the comb and the means whereby it is supported and reciprocated, hence there are no fastening devices requiring removal 30 prior to the removal of the comb.

38 represents a cylindrical tension weight bar, which extends parallel with the comb, and rests loosely on the warp threads 15 below the comb. Said weight bar, which is 35 preferably a length of metal tubing, has two functions, one of which is to maintain a suitable tension on the threads 15. The other function is to stop the loom in case of an excessive tension on said threads, liable 40 to cause excessively tight weaving.

The ends of the bar 38 are loosely confined, and are vertically movable between upright spaced apart guiding flanges 39, on fixed arms 40, having ears 41 at their upper ends, bearing on fixed brackets 42, and fixed to said brackets by bolts 43. The brackets 42 are fixed by bolts 44 to the arch stands 26^a and 35^a.

It will now be seen that the tension weight bar 38 rests loosely in bights of the warp threads 15, and exerts a constant tension thereon. If from any cause the tension of the threads 15 becomes excessive, the bar 38 is raised above its normal position by the 50 threads, until its end portions contact with and move a pair of angular stop levers 45, constituting elements of a well-known mechanism for stopping the loom. Said stop levers are connected by pivot bolts 46, with 55 ears 47 secured to the upright arms 40, and their lower arms have terminals 45^a located in the path in which the bar 38 is movable by an excessive tension on the threads 15. When the bar is raised into contact with 60 the lever terminals 45^a, the upper arms of 65

said levers are depressed and act upon other elements of the stopping mechanism to stop the loom.

In Figure 4 I show conventionally some of the elements of a well known stopping mechanism. I do not, however, show and describe said mechanism in detail, and may use any suitable mechanism which includes terminal elements, such as the levers 45, adapted to be moved by an abnormal upward movement of the tension weight bar 38.

It will be understood that the parts shown by the drawings, not herein referred to and described, are well known elements of a marquisette loom, and do not require description to afford an understanding of my improvements pointed out by the appended claims.

I claim:

1. A loom comprising a marquisette comb having downwardly facing end portions, a pair of rests loosely supporting said end portions, the comb being freely movable upwardly to separate it from said rests, means being provided for preventing separation of the comb from the rests by movements of the comb in other directions, and means for operating one of said rests to reciprocate the comb.

2. A loom comprising a marquisette comb having downwardly facing end portions, a pair of rests loosely supporting said end portions and permitting independent upward movement of the comb, to remove it from the loom, the rests and comb being provided with coupling means preventing independent movement of the comb in other directions, and means for operating one of said rests to reciprocate the comb.

3. A loom comprising a marquisette comb having downwardly facing end extensions, provided with apertures, a pair of rests loosely supporting said extensions, and provided with upwardly projecting pins loosely entering the said apertures, said pins and apertures permitting independent upward movement of the comb to remove it from the loom, and preventing independent movement of the comb in other directions, and means for operating one of said rests to reciprocate the comb.

4. A loom comprising a marquisette comb having apertured extensions at its ends, and rests on which said extensions bear loosely and separably, said rests having upright pins loosely entering the apertures of said extensions, means being provided for oscillating one of said rests and its pin to longitudinally reciprocate the comb, the other rest and its pin being oscillatable by reciprocating movements of the comb.

5. A loom comprising a marquisette comb having apertured extensions at its ends, a positively oscillated rest supporting one of

said extensions, and provided with a pin loosely entering the aperture thereof, and a loosely rocking rest supporting the other extension, and provided with a pin loosely 5 entering the slot thereof.

said bracket having a pin loosely entering 10 the aperture in said extension, and a sleeve mounted to turn or rock on a fixed support, and forming a rest for the other extension, said sleeve having a pin loosely entering the aperture in the extension supported thereby. 15

In testimony whereof I have affixed my signature.

CHARLES F. LAVALLE.

6. A loom comprising a marquisette comb, having apertured extensions at its ends, an oscillatory lever provided with a bracket forming a rest for one of said extensions,
